UNITED STATES PATENT OFFICE

ALBERT J. LINDEMANN, OF MILWAUKEE, WISCONSIN, ASSIGNOR TO A. J. LINDEMANN & HOVERSON COMPANY, OF MILWAUKEE, WISCONSIN, A CORPORATION OF WISCONSIN

HEATER

Application filed February 27, 1928. Serial No. 257,143.

The present improvements relate in general to heaters and more particularly to that type of heater wherein solid fuel is employed as the heating agent.

It has been customary to install coal and wood burning heaters in the basement of homes or other habitable quarters and to conduct the heated air by flues to various parts of the building. While such an installation confines objectionable dust, dirt, etc. to that portion of the building not actually habitated, it has been found inconvenient to attend to, as well as wasteful of fuel and heat. Heaters of varied construction have been designed for installation actually in the rooms to be heated, commonly known as parlor heaters, but have been found to be uneconomical in the use of fuel, wasteful in the application of the heat and unhealthful and unsanitary due to the escape of dirt and smoke into the surrounding quarters.

The present improvements have as their primary object, among others, the provision of a parlor heater which is economical in the use of fuel and heat, reduces to a minimum the dirt accompanying the heater's attendance, eliminates the possibility of smoke entering the room and at the same time provides an article of furniture readily adaptable for placement in any environment.

Another object is to provide an improved heater of sturdy construction, easy to assemble and move, in combination with means for humidifying the circulating air.

Other objects and advantages of the various details and arrangement of parts will be obvious to those skilled in the art upon reference to the accompanying drawings in which:—

Fig. 1 is a perspective of the improved heater, with parts broken away to show details of construction;

Figs. 2 and 3 are details;

Fig. 4 is a side view of the heater in perspective, with top and side removed;

Fig. 5 is a rear view in perspective, with certain parts removed.

The improved parlor heater illustrated comprises an outer casing 1, having a for-

aminated base 2, walls 4, 5, 6 and 7, and a removable top 8 having suitable openings 9 therethrough, all conveniently supported by legs 3 attached to base 2. Said base is preferably of cast iron to afford a sturdy support for the superimposed elements. As aforementioned the base is of foraminated or grid-like construction, for permitting the passage of air therethrough.

The walls of the heater are preferably formed of sheet steel and are bent along their shortest dimensions to form securing flanges 10, whereby said sheets are bolted at their base to base 2. Similar flanges at the top of said sheets are connected in any desired manner for rigidly holding the same in position, and form a support for the removable top or cover 8. Each side sheet or wall 4, 5, 6, and 7 is bent at the edges of its greatest dimension to form outwardly extending flanges 11 and 12, said flanges being so constructed that upon assembly of the casing, as illustrated in Fig. 1, the flange 11 of one sheet and flange 12 of the adjacent sheet abut along the line where bent and diverge, thereby forming a pair of divergent vertically extending flanges providing a dove-tailed corner for the casing at each juncture of the sheets. A tubular member 13 having a longitudinal slot is provided at each such corner of the casing for presenting a finished appearance and holding the side walls in place. This member 13, see Fig. 2, embraces the aforementioned contiguous flanges 11 and 12 and is applied thereto by sliding said member longitudinally from one end of said flanges to the other.

All of the aforementioned parts have a porcelain enamel finish and are suitably grained to simulate wood, thereby presenting a furniture finish to the casing. The cover 8 is relatively light in weight, being made of porcelain, to facilitate removal and is likewise finished to correspond with the casing.

The walls of the casing are further provided with louvers 14 as illustrated, and on the inner side of sheets 5 and 7, a false or inner lining 15 is mounted in spaced rela-

tion, extending from immediately above the louvers 14, to the top of the casing, thereby forming a vertical air duct 16 (see Fig. 5) on two opposite sides of the casing. The front wall 4 has the usual fuel feed opening 17 with the door 18 for closing the same, as well as ash-pit door 19, having suitable damper 20.

The heating unit within casing 1 comprises the ash-pit 21, grate (not shown), fire box 22 and combustion chamber 23, all being of rugged cast iron for resisting great heat, the fire box and combustion chamber being provided with corrugations affording strength and durability, as well as materially increasing the heating surface. The ash pit 21 is securely mounted on base 2 of the casing, with fire pot 22 bolted thereto, chamber 23 in turn being bolted to the top of pot 22. The arrangement and position of these parts is such, that the heating unit is suitably spaced from the casing walls.

A particular feature of the assembly just described resides in the provision of a smoke consumer. Around the top of the fire pot 22 is an annular air duct defined by a plurality of segmental bars 24 in the form of a ring. These bars (see Fig. 3) are curved, as illustrated and have slots 25 in their lower edge. When bolted about the upper periphery of the fire box and within same, an annular air duct is defined between the fire pot wall and the wall of the bars 24. Free communication between said duct, fire box and combustion chamber is afforded, however, through slots 25. Said duct also communicates with the space intervening the fire pot and casing wall 4 by means of two ports 26 through the upper front portion of the fire pot, said ports being provided in register with said duct, whereby the front segmental bar 24 encloses same. A suitable damper 27 for controlling ports 26, is provided, being operable by rod 28 and handle 29, exteriorly of the front wall 4 and beneath fire door 18. Accordingly when damper 27 is open, air is free to pass from the space intervening the heating unit and casing, through ports 26, into the aforementioned annular air duct defined by segmental bars 24. Whence said air fills said duct and escapes into the fire pot and combustion chamber through slots 25.

The combustion chamber is provided with the usual opening defined by offset casting 30 in register with casing opening 17, thereby affording a fuel inlet to the fire box, for coal, coke or wood. An arcuate tube or flue 31, of elbow form, passes through the chamber 23, entering same at one side thereof, passing out the top 32 thereof, at which point a removable grate 33 is seated across said flue. An opening 34 (see Fig. 5) for the exit of hot air and gases, is provided in the upper rear portion of chamber 23.

It will be noted, upon reference to Figs. 4 and 5 that a substantial space is provided between the rear of the heating unit and the rear casing wall 6. Vertically mounted within said space in any convenient manner, is U-shaped flue 35, comprising a down comer flue 36, lower horizontal flue 37 and up-going flue 38. A box-like chamber 39 completes the flue or duct 35, and has free communication with the flues 36 and 38, at their upper ends. A flue 40 for discharging heated air and gases to a chimney or other suitable means, is provided at the upper rear portion of chamber 39. Communication between the combustion chamber 23, flue 35 and flue 40, is afforded by pipe 41 connecting opening 34 with chamber 39.

Referring to Fig. 5, the above described construction is illustrated with casing wall 6 and the rear wall of chamber 39 removed. A transverse wall 42 projects a short distance from the base of chamber 39, forming a continuation of flues 36 and 38 and has pivotally supported thereon a damper 43 adapted to be rocked freely from full to dotted line position and vice versa, by handle 44 projecting through casing wall 5. Clean out ports 45 and 46 are provided for flue 35, at the bottom and top thereof respectively. A humidifier in the form of a galvanized iron drawer 47 is positioned on the base 2 and beneath horizontal flue 37. Said drawer is provided with a finished face 48 and handle 49 (see Fig. 1), for withdrawal through the casing 1.

The operation of the improved heater, so far described, is as follows:—When starting the fire in the fire pot, damper 20 is opened and the damper handle 44 is pulled out, so that damper 43 is in the dotted line position of Fig. 5. This causes a direct draft to the chimney from combustion chamber 23, via pipe 41, chamber 39 and flue 40, these elements thereby affording a direct discharge flue for the hot air and gases from said chamber. The fire having been well started, damper 43 is rocked to full line position whereby the said hot air and gases are directed into the U-shaped flue 35, passing through flues 36, 37, 38, chamber 39 to discharge flue 40. These elements thereby affording an indirect discharge flue for the products and air from chamber 23.

The caloric value of these gases is well known, and by diverting same through this return flue or economizer 35, heat which otherwise would be carried directly to the chimney and lost, is applied to a useful purpose. In thus by-passing the direct flue, the gases heat the walls of the return flue 35, which radiate the heat to the air within casing 1, the spent gases continuing out through flue 40. The radiating surface of the fire pot and combustion chamber is thus augmented by this auxiliary radiating sur-

face, which may be more than half the radiating surface of the heating unit itself. Being away from direct contact with the fire, the economizer 35 may be of thinner iron than that of the heating unit, thereby facilitating heat transfer. It is obvious that a great saving of fuel and heat results in the provision of this economizer, since the utilization of the discharged products of combustion to heat an additional radiating surface, produces a greater per cent of heat from a given quantity of fuel than has heretofore been the practice.

It will be noted here that the present improvements embody a heater of the air circulating type as well as a heater dispensing heat by radiation, thus presenting a dual function heating unit. When fire is present in the fire pot, a constant circulation of air is established through the casing. The cooler air adjacent the floor, upon which the heater rests, enters the casing through the foraminated base 2, as well as louvers 14, ascends the space intervening the casing heating unit and economizer, and discharges through openings 9 in cover 8 to the room. During this ascent, a portion of the air passes through the vertical air duct 16, in which it is heated, other portions surround the heating unit and economizer, and are heated thereby, some of which enters the elbow-form duct 31, being thus directed through the chamber 23 directly over the fire, escaping through grate 33 and thence through cover 8. A constant flow of cool air into the lower part of the heater and hot air from the top thereof, is thus maintained. The diversion of some of the circulating air into duct 31, where it is super-heated, has been found to greatly increase the efficiency of the heater.

The humidifier 47 is provided with a quantity of water and has an open top, as illustrated. Accordingly the circulating air absorbs moisture therefrom and carries it into the room, thereby maintaining the desired humidity. It may be noted here that in addition to the admission of air, the louvers 14, by their design, also deflect the heat radiated from the heating unit downward toward the floor. Should less heat be desired, the gases and hot air from the combustion chamber may be passed directly to the chimney, without diversion through return flues 35, by moving damper 43 to the dotted line position (Fig. 5), thus cutting out the auxiliary radiating surface of said flues.

The smoke consumer functions as follows:—By turning handle 29 to open position an auxiliary draft is established through ports 26, through the annular air duct formed by bars 24 and slots 25 to the interior of the heating unit. This air becomes heated as it passes around said duct and dis-

charges radially from all sides through slots 25 which throw it downward directly over the fire. Gases and smoke are consumed by the presence of this added air directly over the area of combustion. Greater heating energy is thus derived from the fuel. This feature has been found particularly effective where soft coal is employed and obviates objectionable smoke attending such use. An added feature, for preventing the escape of smoke into the room is illustrated in Fig. 1. At the top of opening 17, a plate 50 is pivotally mounted and depends a short distance across said opening thereby forming a smoke curtain, preventing escape of smoke and gases from the fire pot, into the room, when door 18 is open.

Referring further to Fig. 1, a plate 52 is pivotally mounted at its base, along the bottom of opening 17. Said plate is overbalanced for swinging by gravity away from the interior of the casing. When door 18 is open, plate 52 projects outwardly through opening 17 as seen in Fig. 1. A friction plate 53 is suitably mounted on the ventilated lining of door 18, and contacts with the corner 54 of plate 52 as door 18 is moved to closing position. Plate 52 is thus forced inwardly and upwardly about its pivotal mounting, until the door is completely closed, in which position it is held by the door across opening 17. Obviously, opening movement of door 18 permits plate 52 to fall by gravity to the position in Fig. 1. When door 18 is closed, plates 50 and 52 are extending toward one another in opposed relation.

Accordingly the position of plate 52 is controlled by door 18, and when in the illustrated position, said plate affords a coal chute and prevents any coal or dust from falling onto the floor. The spout of a coal scuttle may be rested on plate 52, and fuel thereby fed into the fire pot, any dust or coal dropping, through careless handling of the scuttle, onto plate 52, which is ultimately thrown into the fire pot upon closing of the door. If the scuttle is tipped so far as to contact with upper plate 50, the latter will be swung inwardly and will in no way interfere with tipping of the scuttle. Upon removal of the latter, plate 50 will return by gravity to the illustrated position.

The fire pot 22 has a pair of projecting lugs 55 cast integrally therewith or otherwise secured thereto in spaced relation. A pair of such lugs are provided on opposite sides of said pot, and each lug has rigidly secured thereto, an arm 56 projecting upwardly and outwardly through a slot 57 in the adjacent casing wall. A lifting handle or bar 58 joins the ends of these arms on each side of the heater and is removably secured thereto by ornamental knobs 59. This organization facilitates assembly and

disassembly of the casing about the heating unit, as is obvious. The arms 56, handles 58 and knobs 59 are suitably finished to correspond with the casing finish. These elements afford a convenient and sturdy means for moving the heater, the lifting energy being applied directly to the heaviest unit, interiorly of the casing 1. When not serving as a lifting means, handles 58 may be utilized for supporting towels or other articles, as desired.

In the provision of a light removable cover 8, it is apparent that same may be removed and the top 32 of chamber 23, as well as grate 33, utilized for culinary purposes.

Various modifications, within the scope of the present improvements, will be apparent to those skilled in the art.

20 I claim:

1. A heater of the character described comprising an outer casing having a plurality of louvers in each face, and an open top and base, an inner lining associated with at least one face of said outer casing and defining a vertical air duct, a combustion chamber having an arcuate air duct therethrough housed in said casing, a discharge flue for said chamber, a U-shaped circulation flue within said casing communicating with said discharge flue and a damper controlling said flues.

2. A heater of the character described comprising an inner heating unit and a casing surrounding same, a pair of spaced arms secured to opposite sides of said unit and projecting through slots in said casing and a handle removably joining each pair of arms outside said casing.

3. A heater of the character described comprising an outer casing having louvers, a fire pot supported within said casing and terminating above said louvers, a combustion chamber supported on said fire pot and having an outlet flue, a plurality of ports through the upper wall of said pot, a damper controlling said ports and a peripheral air duct removably mounted within said fire pot, communicating with said ports and the interior of said fire pot.

4. A heater of the character described comprising an inner heating unit, a casing surrounding same, a laterally extending gripping handle exterior to said casing, and means connected with said handle, extending through said casing and secured to said heating unit at spaced points.

Witness my hand this 23d day of February, 1928, at the city of Milwaukee, in the county of Milwaukee, State of Wisconsin.

ALBERT J. LINDEMANN.
